UNITED STATES PATENT OFFICE.

AUGUST N. RITZ, OF MILWAUKEE, WISCONSIN.

DESIGN FOR A PASTE-JAR.

SPECIFICATION forming part of Design No. 35,669, dated February 4, 1902.

Application filed December 2, 1901. Serial No. 84,487. Term of patent 14 years.

To all whom it may concern:

Be it known that I, AUGUST N. RITZ, a citizen of the United States, residing at Milwaukee, in the county of Milwaukee and State of Wisconsin, have invented and produced a new and original Design for Paste-Jars; and I do hereby declare the following to be a full, clear, and exact description of the same, reference being had to the accompanying drawings, forming a part thereof.

In the said drawings, Figure 1 is a plan view, and Fig. 2 is a side elevation, of a paste-jar embodying my new design.

My design relates to the new and original shape or configuration of the article.

The leading or essential feature consists in the unitary design for a paste-jar made the subject of illustration, comprising the shape of the main cylindrical receptacle A and the outer receptacle B, rising to the same height as the main receptacle A, but of less diameter, and united thereto closely all the way from the base to a point adjacent to the top, without space or separation between the two receptacles save a narrow separating-space 25 at the upper end.

Minor features of said design comprise the circumferential ribs *a b c* on the part A and the corresponding circumferential ribs *a' b' c'* on the part B in horizontal line with the first-named ribs.

Having thus described my invention, what I claim as new, and desire to secure by Letters Patent, is—

The design for a paste-jar, substantially as herein shown and described.

In testimony whereof I affix my signature in presence of two witnesses.

AUGUST N. RITZ.
